CENTRIFUGAL MOLD AND LINER

Ernest R. Olsen, Grand Haven, and Rudolph F. Flora and Clifford J. Lonnee, Muskegon, Mich., assignors to Hastings Manufacturing Company, Hastings, Mich.

Application January 9, 1950, Serial No. 137,506

8 Claims. (Cl. 22—113.5)

1

This invention relates to improvements in centrifugal mold and liner.

This application is a continuation in part of our application for Letters Patent, Serial No. 710,449, filed November 18, 1946, now Patent No. 2,495,817; issued January 31, 1950.

The main objects of this invention are:

First, to provide a permanent centrifugal mold and a liner therefor presenting a continuous substantially smooth surface against which the metal is cast.

Second, to provide a centrifugal mold and liner in which the liner is a preformed asbestos or other heat resisting sheet which may be quickly and conveniently inserted and acts to provide a continuous liner for the mold wall.

Objects relating to details and economies of the invention will appear from the description to follow. The invention is pointed out in the claims.

A preferred embodiment of the invention is illustrated in the accompanying drawings, in which:

Fig. 1 is a fragmentary side elevational view partially in longitudinal section of a centrifugal mold embodying our invention.

Fig. 2 is an enlarged fragmentary perspective view of the mold sectioned on a line corresponding to line 2—2 of Fig. 1.

Fig. 3 is an enlarged fragmentary transverse section illustrating details of the arrangement of the liner in relation to the mold wall.

Fig. 4 is a fragmentary sectional view corresponding to that of Fig. 3 of a modified form or embodiment of our invention.

Our present invention is an adaptation of and in some respects an improvement upon the invention disclosed in our Patent No. 2,489,280, issued November 29, 1949. Our present invention provides for a liner completely covering the mold cavity wall and at the same time permitting expansion of the liner into effective supported relation to the mold wall and permitting it to conform to the expansion of the mold wall such as may result from casting heat and the removal of the liner with the casting.

In the drawing the mold wall 1 is shown as generally cylindrical and its inner end wall 2 is carried by the shaft or spindle 3. The outer annular end plate 4 provides a central opening 5. This end plate is commonly hinged or otherwise removably supported, the details not being illustrated as they form no part of our present invention.

The inner surface of the mold cavity wall is

provided with a ventilating means, that illustrated being in the form of longitudinal grooves 6 which grooves are of such width that when the liner 7 is disposed within the mold it extends across the grooves but does not enter into the same. The dimensions of the grooves 6 as illustrated are somewhat exaggerated in proportion to the wall thickness and diameter. The end plate 4 is provided with an annular groove 8 on its inner side communicating with the ventilating grooves 6 when the end plate is in position. The groove 8 has vents 9 opening to the outer side of the plate. In addition to the ventilating grooves 6 the mold wall has a relatively wide, shallow, longitudinally extending liner edge receiving groove 10 extending from end to end thereof.

The preformed sheet liner 7 is of heat resisting material desirably of sheet asbestos and is bendable so that it may be formed into a roll and inserted longitudinally into the mold cavity. The dimensions of the liner exceed somewhat the internal circumferential diameter of the mold wall so that the edges of the liner overlap when the liner is expanded into supported relation to the mold wall. One edge portion 11 of the liner of substantial width is disposed in the liner receiving groove 10, the liner being sufficiently flexible so that when the liner is subjected to the weight of the metal resulting from the centrifugal action of the mold, the portion 11 offsets at 12 and is supported by the bottom of the groove. The other edge portion, designated 13, of the liner laps upon the inner side of the portion 11, the liner being of such width that its edge 14 is closely adjacent to the offset 12. The edge 15 of the liner desirably abuts the edge 16 of the groove to aid in the correct positioning of the liner within the mold.

The lapsing portions of the liner are not connected so that the liner is free to expand into supported relation with the mold wall even though the mold wall may expand when it becomes heated as a result of casting operations. This insures a complete fitting support of the liner with the mold wall and the metal will not flow behind the liner. This lapsing of the liner avoids any chill line, that is, the whole surface of the mold is covered. Desirably a ventilating groove 17 is provided at the bottom of the liner receiving groove 10.

The heat resistant material, such as asbestos, for example, is commonly formed into a sheet with a binder, commonly of starch or the like. This binder is consumed by the heat and the

ventilation of the mold wall permits the escape of the products of combustion. The ventilating groove 17 is desirable as there is a double thickness of the liner at the overlap and therefore it is desirable that the products of combustion escape.

In the modification shown in Fig. 4 one edge of the groove or recess 18 merges into the mold wall with curved lines, thus eliminating an offset of the liner as at 12. The edge 15 of the liner is abutted against the edge 19 of the recess while the inner edge portion of the liner laps upon the portion disposed within the recess.

With this structure and arrangement of parts the liner formed of sheet asbestos may be quickly and easily inserted and accurately positioned. Desirably the liner has sufficient resilience so that it is merely necessary to roll the liner up in a cylindrical form of less diameter than the mold and insert it so that the edge 16 thereof engages the edge of the groove and the liner is then released and allowed to expand within the mold in supported relation with the walls of the mold. If it does not closely contact the walls of the mold when thus inserted it will expand into supported contact therewith when the metal is poured and as the liner is subjected to the centrifugal thrust thereof. The liner prevents undesirable chill and eliminates the necessity for heat treatment before machining. Also the castings may be made quite close to size and thereby minimizing machining.

We have illustrated and described highly practical embodiments or adaptations as we believe this disclosure will enable those skilled in the art to embody or adapt our invention as may be desired.

Having thus described our invention, what we claim as new and desire to secure by Letters Patent is:

1. A casting apparatus comprising a permanent centrifugal mold having longitudinally extending ventilating grooves in its inner surface and a longitudinal liner receiving groove of substantially greater width than depth, a nonmetallic bendable preformed sheet liner of heat resisting material positioned in said mold in supported facing relation with the wall thereof and across said ventilating grooves therein, one longitudinal edge portion of the liner being disposed in said liner receiving groove in outwardly offset supported relation to the bottom thereof, the other edge portion of the liner being disposed in side overlapping relation to a portion of the liner disposed in the groove the overlapping edge being closely adjacent to the offset, the depth of the liner receiving groove being approximately equal to the thickness of the liner.

2. A casting apparatus comprising a permanent centrifugal mold having longitudinally extending ventilating grooves in its inner surface and a longitudinal liner receiving groove of substantially greater width than depth, a nonmetallic bendable preformed sheet liner of heat resisting material positioned in said mold in supported facing relation with the wall thereof and across said ventilating grooves therein, one longitudinal edge portion of the liner being disposed in said liner receiving groove in outwardly offset supported relation to the bottom thereof, the other edge portion of the liner being disposed in side overlapping relation to a portion of the liner disposed in the groove the overlapping edge being closely adjacent to the offset.

3. A casting apparatus comprising a perma-

5. A casting apparatus comprising a permanent centrifugal mold having longitudinally extending ventilating grooves in its inner surface and a longitudinal liner receiving groove of substantially greater width than depth, a nonmetallic bendable preformed sheet liner of heat resisting material positioned in said mold in supported facing relation with the wall thereof and across said ventilating grooves therein, one longitudinal edge portion of the liner being disposed in said liner receiving groove in outwardly offset supported relation to the bottom thereof, the other edge portion of the liner being disposed in side overlapping relation to a portion of the liner disposed in the groove the overlapping edge being closely adjacent to the offset, there being a relatively narrow ventilating groove in the bottom of said liner receiving groove and across which the edge portion of the liner disposed in the liner receiving groove extends.

20 4. A casting apparatus comprising a permanent centrifugal mold having a generally cylindrical mold cavity wall surface and a liner receiving groove of substantial width extending longitudinally thereof, and a nonmetallic longitudinally split preformed bendable sheet liner of heat resisting material positioned in said mold cavity in supported facing relation to the wall thereof, one edge portion of the liner being positioned in the liner receiving groove in supported relation to the bottom thereof, the other edge portion of the liner being disposed in overlapping relation to the inner side of the edge portion of the liner disposed in the groove but being unconnected therewith permitting expansive movement of the liner, the groove being of a depth substantially equal to the thickness of the liner.

5. A casting apparatus comprising a permanent centrifugal mold having a generally cylindrical mold cavity wall surface and a liner receiving groove of substantial width extending longitudinally thereof, and a nonmetallic longitudinally split preformed bendable sheet liner of heat resisting material positioned in said mold cavity in supported facing relation to the wall thereof, one edge portion of the liner being positioned in the liner receiving groove, the other edge portion of the liner being disposed in overlapping relation to the inner side of the edge portion of the liner disposed in the groove but being unconnected therewith permitting expansive movement of the liner.

6. A casting apparatus comprising a permanent centrifugal mold having a longitudinally extending recess in its mold surface and a nonmetallic liner of sheet heat resisting material disposed in the mold in supported relation to the mold cavity wall, one edge of the liner being positioned in said recess, the other edge of the liner being disposed in lapping relation to the edge portion of the liner disposed in the recess but being unconnected therewith permitting free expansion of the liner into contacting supported relation to the mold surface.

65 7. A casting apparatus comprising a mold cavity wall having a longitudinal inwardly facing recess therein, and a nonmetallic preformed bendable sheet liner of heat resisting material disposed within the mold cavity in supported relation to the wall thereof with one edge of the liner disposed in said recess, the other edge of the liner being disposed in overlapping relation to the edge disposed in the recess but being free therefrom.

8. A casting apparatus comprising a mold cav-

ity wall having a longitudinal inwardly facing recess therein extending from end to end thereof, and a nonmetallic bendable preformed sheet liner of heat resisting material disposed within the mold cavity in supported relation to the wall thereof with one edge of the liner within said recess and the other edge of the liner in overlapping side by side relation to the edge disposed in the recess and slidably relative thereto.
